(57) **CLAIM**

The ornamental design for a sucker of a plunger, as shown and described.

DESCRIPTION

FIG. 1 is a perspective view of a sucker of a plunger showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof; and,

FIG. 8 is an environmental perspective view thereof with the broken lines showing a handle being for illustrative purposes only and forming no part of the claimed design.
